CLAIM

The ornamental design for a tail light for automobile, substantially as shown and described.

DESCRIPTION

FIG. 1 is a perspective view from the front and to one side of the tail light for automobile showing my new design;

FIG. 2 is a side elevational view thereof;

FIG. 3 is a front elevational view thereof;

FIG. 4 is a top plan view thereof;

FIG. 5 is a rear perspective view; and

FIG. 6 is an elevational view taken from an end opposite that shown in FIG. 2.

FIG. 1.

FIG. 2.

FIG. 3.

FIG. 4.

FIG. 5.

FIG. 6.
